UNITED STATES PATENT OFFICE.

EMILE UTARD AND ALEXANDER GIMONET, OF NEW YORK, N. Y., ASSIGNORS TO H. & G. KLOTZ & CO., OF NEW YORK, N. Y., A FIRM.

MACHINE FOR DRYING BOTTLES.

No. 901,757.

Specification of Letters Patent.

Patented Oct. 20, 1908.

Application filed March 26, 1908. Serial No. 423,321.

To all whom it may concern:

Be it known that we, EMILE UTARD and ALEXANDER GIMONET, citizens of the United States, and residents of New York, county 5 and State of New York, have invented Improvements in Machines for Drying Bottles, of which the following is a specification.

In preparing bottles for the reception of alcoholic preparations, as perfumes, and 10 toilet liquids, it is essential that their interiors be perfectly clean and free from water and aqueous vapors for such contents to preserve a bright and unclouded appearance. To attain this end it is now the practice to manually rinse bottles designed for 15 such uses with alcohol after they have been thoroughly washed with water; this, to obtain perfect results, is a very expensive besides being a tedious and slow process, and 20 the object of this invention is to provide a simple and effective machine for drying bottles; the drying agent of which is air under pressure and suitably heated.

To accomplish this our machine comprises 25 a series of perforated nozzles over which the bottles are placed and supported by suitably shaped cups, said nozzles extending upwardly from an air pipe, which is preferably circularly formed, or as a ring, connected by hollow spokes to a central hub, adapted to be rotated on a central support, 30 manually or by power, so that the bottles may at one part or side of the machine be readily placed over and removed from the 35 nozzles. To the end that this may be done without undue loss of the heated air and inconvenience to the operator a suitable valve device is provided in the hub of the bottle carrying and drying ring adapted to cut off 40 the air supply from successive sections of the ring as they pass by the operator. The air as it passes under pressure through the ring is suitably heated, this being preferably done by means of gas jets so arranged that 45 the flames will act on the under side of the air ring. These with other novel features of construction will now be more fully described by reference had to the accompanying drawings, in which:—

50 Figure 1 is an elevation of our improved bottle drying machine. Fig. 2, Sheet 2 is a general plan view of the same, showing the air supply ring partly in section. Fig. 3, Sheet 3 is a plan view of the gas heater of

the machine showing also the central support. Fig. 4, Sheet 4 is an enlarged vertical sectional view of the central support of the bottle holder and the valve device. Fig. 5, Sheet 4 is a similar view of a part of the air ring, bottle holder and heater. Fig. 6, Sheet 60 3 is a horizontal section of Fig. 4, taken on the line 6, 6. Fig. 7, Sheet 2 is a reproduction of the lower part of Fig. 5, with an additional feature. Fig. 8, Sheet 2 is a view similar to Fig. 6, on a smaller scale, showing 65 a modification in the construction of the valve. Fig. 9, Sheet 4 illustrates a portion of the bottle holding ring and air nozzles, showing the adaptation for treating or drying large bottles, and Fig. 10, Sheet 4 shows 70 one of the air nozzles provided with a cap or thimble for closing the orifices.

The air and bottle carrying ring is formed of hollow annular sections of pipe *a*, from which extend towards the center of the ring 75 hollow spokes *b*, and the ends of the sections between the spokes are joined together by couplings with partitions or plugs *c* located between the adjacent ends of the pipe sections, thus isolating the sections, each one by 80 its hollow spoke *b* being individually placed in communication with the air supply. Six such sections are shown, but it is evident there may be any desired number to meet special requirements. The inner ends of the 85 spokes *b* are connected to a hub *d* formed interiorly with an angular bearing which rests on a correspondingly formed seat *e*, provided with a port or port openings *f* arranged opposite the openings of the hub *d* communicating with the hollow spokes *b*, said port or 90 port openings *f* extending for the most part circularly around the seat *e*, leaving a land or face *g* of sufficient extent to cover one of the spoke openings for a considerable time 95 during the rotation of the ring *a*. The ribs *h* connect the upper and lower parts of the seat *e* and impart strength thereto. The seat *e* is secured in a plate *i*, which in turn is secured, by bolts, to the top of the central supporting 100 column *j*; and from this plate extends a discharge pipe *k* provided with a cock *l*, by means of which aqueous and other deposits may be allowed to escape from the interior of the valve device; see Figs. 4 and 6.

A lubricant may be supplied to the working surfaces of the parts *d* and *e* from a cup *m*.

From the upper side of the air ring *a* extend a series of nozzles *n*, equidistantly arranged, on each of which is placed a cup *o* adapted to hold a bottle *p* with the nozzle *n* extending therein. The nozzles have orifices in their ends and sides, through which the heated air passes and impinges against the interior of the bottles, escaping by their mouths through holes *q* formed in the bottoms of the cups *o*, and carrying away all water that may be inside the bottles, leaving them perfectly dry; see the enlarged sectional view Fig. 5.

The means for heating the air comprises an annular gas pipe *r* arranged beneath the air ring *a*, and supported by legs *s*. One end of this pipe *r* is closed and the other one is provided with a gas pipe *t* and an air pipe *u* provided, as shown in Fig. 3, respectively with cocks *v* and *w* for regulating the supply of gas and air in suitable proportions for perfect combustion at the burners *x*, which are arranged on the top of the pipe *r* immediately below the air pipe *a*. If thought advisable or necessary an annular hood *y* may be placed on and carried by the air ring *a* with its depending sides surrounding the burners *x*, to efficiently cause the heat of their flames to act on and heat the air in the air ring *a*.

The hollow spokes *b* of the air ring *a* are provided with union connections *z*, thus permitting the ring to be readily removed and if desired to be replaced by another having different kind, number and size of air nozzles and cup bottle holders.

Air under suitable pressure for the purpose of this machine is supplied to the interior of the valve *d*, *e*, from any convenient fit source of compressed air supply, by the pipe *1*, a vertical leg of which is screwed in or otherwise secured to the upper end of the seat *e* of the valve, and this pipe is provided with a stop cock *2*, by which the air may be regulated in quantity desired to the air ring *a* and nozzles *n*, or entirely cut off therefrom.

As before stated the bottle drying and carrying ring may be rotated manually or by power, so that the bottles successively or sections of them successively may be brought before the operator, or operators, who will be located at that part of the machine where the air will be cut off from the sections *a* of the air ring, which location is opposite the part or land *g* of the stationary part *e* of the central air controlling valve; and it will be observed, by reference had to Fig. 3, that there is a considerable gap between the ends of the circular gas pipe *r*, so that there is no heat applied to the air ring where the bottles are placed over and removed from the drying means. When it is desired to apply power for rotating the air ring, to impart a continuous steady motion thereto,

it is proposed to attach to the periphery of the air ring a circumferential gear *3*, into which meshes a pinion *4* secured to the upper end of a vertical shaft *5*; bearings *6*, *6* for which may extend from one of the supporting legs *s* of the gas pipe *r*; and this shaft *5* may be rotated at variable speeds by a cone pulley *7*, which receives motion through the medium of a belt *8* from any suitable motor or driving shaft provided with an accordant cone pulley. This construction provides a simple means for this purpose, but it is evident any suitable mechanical driving device may be employed.

The arrangement of the air nozzles *n*, as shown in the main views of the drawings, is such that each one is adapted to carry and dry a small size bottle, several being shown at Fig. 1 by dotted lines *p*, and when it is desired to dry larger size bottles by the machine having the arrangement of air nozzles as shown, then the supporting cups *o* for small bottles are removed and larger cups applied to some of the nozzles only, the intervening nozzles being closed or made inoperative by a cap or thimble *9*, as illustrated at Fig. 10, which fits snugly over the tops of the nozzles to fully cover all of the air issuing orifices, thus avoiding loss of heated air and the inconvenience accruing from the free discharge of the same. At Fig. 9, showing a portion of the air ring *a* and nozzles *n*, the alternate nozzles are made inoperative by the caps *9* and the active nozzles are provided with supporting cups *10* adapted to hold larger bottles *p* than those shown in the other views.

It will be understood that the port opening of the stationary part *e* of the central valve may be varied as to size to open up as much of the air ring or as many of its sections *a* to the air supply as desired, depending on the relative amounts of time required to handle the bottles and to have them submitted to the heated air for the thorough drying of them. As for instance the relative circumferential extents of the port and the land of the valve which closes the openings of the hollow spokes *b* may be proportioned as illustrated at Fig. 8, in which view the port *11* exposes practically only one of the sections of the air ring to the source of air supply, and all of the other sections at the same time are cut off from the air supply by the extended face or land *12* of the valve; and the machine so arranged is well adapted for use in washing bottles without any material changes being made in other parts of the machine, a supply of water through the pipe *1* being of course substituted for the compressed air supply. The gas heater device for this use may be eliminated, or it may in some cases be advantageously used to heat the water,

as thereby some bottles might be better and more quickly cleaned and require less time to drain.

We claim as our invention:—

5 1. In a machine of the character described, a central support, a carrier for bottles consisting of a plurality of hollow sections fitted to rotate on the central support, perforated nozzles and bottle supports attached to the 10 hollow sections of the carrier, an air supply pipe, means for admitting air therefrom to the hollow sections successively, and means for applying heat to the hollow sections of the carrier and the air passing therethrough 15 to the perforated nozzles.

2. In a machine of the character described, a central support, a carrier for bottles consisting of a plurality of hollow sections fitted to rotate on the central support, perforated 20 nozzles and bottle supports attached to the hollow sections of the carrier, an air supply pipe, means for admitting air therefrom to some of the hollow sections, means for continuously rotating the carrier, and means for 25 heating the hollow sections only through which the air is passing.

3. In a machine of the character described, a chambered central support, a carrier for bottles consisting of a plurality of hollow 30 sections fitted to rotate on the central support, perforated nozzles and bottle supports attached to the hollow sections of the carrier, an air supply pipe connected to the upper part of the chamber of the central support, means for admitting air from this 35 chamber successively to the hollow sections as they are rotated on the central support, a pipe extending from the lower part of the chamber of the central support for the discharge of aqueous and other deposits precipitated from the air, and means for heating the carrier sections only through which 40 the air is passing.

4. In a machine of the character described, 45 a central support, a carrier for bottles consisting of a plurality of hollow sections fitted to rotate on the central support, perforated nozzles and bottle supports attached to the hollow sections of the carrier, an air supply pipe, means for admitting air therefrom to the hollow sections successively, means for closing the perforations of some of the nozzles, as the alternate ones, at will, and means for applying heat to the hollow sections of the carrier and the air passing therethrough 55 to the perforated nozzles.

5. In a machine of the character described, a hollow ring, a central support, a chambered hub fitted to rotate on said central support, hollow spokes connecting the hollow ring and hub, perforated nozzles extending 60 upwardly from the hollow ring, bottle supports for holding bottles over the nozzles; a supply pipe connected to the central support

and an annular gas pipe located beneath the 65 hollow ring and having burners arranged to direct the burning gas against the ring.

6. In a machine of the character described, a hollow ring, a central support, a chambered hub fitted to rotate on said central support, 70 hollow spokes connecting the hollow ring and hub, perforated nozzles extending upwardly from the hollow ring, bottle supports for holding bottles over the nozzles, a supply pipe connected to the central support, 75 an annular gas pipe located beneath the hollow ring and having burners arranged to direct the burning gas against the ring, and a guard carried by the hollow ring having depending sides surrounding the gas burner. 80

7. In a machine of the character described, a ring provided with hollow sections, a hollow spoke connected to each section, a chambered hub connected to the inner ends of the spokes, a central support for and on which 85 the hub is free to rotate, an air supply pipe connected to the central support, means for controlling the flow of the air successively to the hollow sections of the ring, an annular gas pipe provided with gas burners located 90 only under those portions of the sections of the ring to which the air is permitted to flow, perforated nozzles extending upwardly from the ring, and bottle supports for holding bottles over the nozzles. 95

8. In a machine of the character described, a ring provided with hollow sections, a hollow spoke connected to each section, a chambered hub connected to the inner ends of the spokes, a central support for and on which 100 the hub is free to rotate, an air supply pipe connected to the central support, means for controlling the flow of the air successively to the hollow sections of the ring, an annular gas pipe provided with gas burners located 105 only under those portions of the sections of the ring to which the air is permitted to flow, perforated nozzles extending upwardly from the ring, bottle supports for holding bottles over the nozzles, and means for rotating the ring. 110

9. In a machine of the character described, a hollow ring, a central support, a chambered hub fitted to rotate on said central support, hollow spokes connecting the hollow ring and hub, perforated nozzles extending upwardly from the hollow ring, thimbles or caps for closing the perforations of more or less of the nozzles at will, bottle supports for holding bottles over the nozzles, 120 and a supply pipe connected to the central support.

10. In a machine of the character described, a hollow ring, a chambered hollow support, a chambered hub fitted to rotate on 125 said central support, hollow spokes connecting the hollow ring and hub, union connections applied to the hollow spokes, perfo-

rated nozzles extending upwardly from the hollow ring, bottle supports for holding bottles over the nozzles, and a supply pipe connected to the upper part of the chamber of the central support.

11. In a machine of the character described, a ring provided with hollow sections, a hollow spoke connected to each section, a conical chambered hub connected to the inner ends of the spokes, a central support provided with a conical valve seat for and on which the hub is free to rotate and whereby the openings to the hollow spokes are successively closed, a supply pipe connected to the upper part of the central support, a discharge pipe extending from the lower part of the chamber of the central support, perforated nozzles extending upwardly from the ring, and bottle supports for holding bottles over the nozzles.
12. In a machine of the character described, a ring provided with hollow sec-

tions, a hollow spoke connected to each section, a conical chambered hub connected to the inner ends of the spokes, a central support provided with a conical valve seat for and on which the hub is free to rotate and whereby the openings to the hollow spokes are successively closed, a supply pipe connected to the central support, perforated nozzles extending upwardly from the ring, bottle supports for holding bottles over the nozzles, a circumferential gear secured to the periphery of the ring, a pinion meshing in said gear, and means for driving the pinion at variable speeds.

In testimony whereof, we have hereunto subscribed our names this 23rd day of March, 1908.

EMILE UTARD.
ALEXANDER GIMONET.
